UNITED STATES PATENT OFFICE.

FRANK E. PAYNE, OF CHICAGO, ILLINOIS.

CONDENSER.

1,427,318.

Specification of Letters Patent. Patented Aug. 29, 1922.

Application filed November 28, 1921. Serial No. 518,151.

To all whom it may concern:

Be it known that I, FRANK E. PAYNE, a citizen of the United States, residing at Chicago, in the county of Cook and State of Illinois, have invented certain new and useful Improvements in Condensers, of which the following is a specification.

This invention relates to improvements in condensers, and more particularly to the ferrules commonly employed to retain the condenser tube packings in place and to prevent or limit outward displacement of the tubes with respect to the tube sheets.

It has been the practice heretofore to provide the ends of all the tubes in a condenser with individual ferrules, which have screw-threaded engagement with the tube sheets around the tube ends and serve as packing retainers. They also prevent longitudinal displacement of the tubes, the latter result being accomplished by prividing the ferrules with inwardly directed shoulders overlying the ends of the tubes. Since condensers are used employing from 10,000 to 20,000 tubes, it will be seen that these ferrules represent a substantial item, both as regards cost and the time and labor involved in applying the same.

One object of the present invention is to provide a ferrule which may engage not only the end of the tube to which it is applied but also all of the tube ends immediately surrounding it, thus greatly reducing the number of ferrules required to limit the movement of the tubes and thereby effecting a material saving.

Another object is to provide apparatus of this character in which a metallic packing is used, said packing having characteristics which enable it to be swedged into the screw-threaded recesses surrounding the tube ends whereby ferrules are not required to hold the packing in place, such few special ferrules as are used acting merely as stops to be engaged by the tubes in their movement.

Other objects and advantages will be apparent from the following specification, taken in connection with the accompanying drawings, wherein several forms of the invention are illustrated.

In the drawings—

Figure 1 is a fragmentary end view of a condenser showing the tubes projecting through the tube sheet thereof and the ferrules constructed in accordance with the present invention in operative position;

Fig. 2 is a sectional view taken on the line 2—2 of Fig. 1;

Fig. 3 is a longitudinal sectional view taken through a slightly modified form of ferrule,

Fig. 4 is an end view of a further modification of the invention, and

Fig. 5 is a sectional view of another modification.

Referring more in detail to the drawings, a condenser tube sheet is shown at 10, and projecting therethrough are the tube ends 11. The openings 12 in the tube sheet through which the tubes project are slightly enlarged towards their outer ends and a shoulder 13 formed near their inner ends. These enlargements of the openings 12 are screw-threaded as at 14, and adapted to be engaged by the screw-threaded, longitudinally extending sleeves 15 of my improved ferrules, the latter being indicated generally by reference character 16.

The ferrules 16 are of the usual open-ended construction but, according to the present invention, it is proposed to provide the same with transversely extending annular flanges 17 at the outer end of the sleeves 14. Said flange projects both outwardly and inwardly from said sleeve forming shoulder 17^a and 17^b, the latter being of considerable extent as compared to the former. The tubes in a condenser are mounted in rather close proximity and according to the present invention it is proposed to construct the flange 17 at the end of the ferrule so that it extends outwardly as shown in Fig. 1, having a shoulder 17^b which will overlie a portion of the exposed ends of all of the tubes immediately surrounding the one to which the ferrule is directly applied. The small, inwardly directed shoulder 17^a overlies the end of the tube to which the ferrule is applied, as shown more clearly in Fig. 2.

As is well known, it is customary to apply packing of some suitable type, usually fabric, around the tubes between the walls of the latter and the adjacent walls of the openings in the tube sheets through which the ends of the tube project. I employ preferably, a flexible metallic packing, 18. In applying the same in the form of rings, said packing is tamped or firmly pressed inwardly against the shoulder 13, during which operation it is also swedged outwardly into the screw threads 14. After this is done, a ferrule is usually applied by screwing the same

into position against the outer end of the packing, as shown in Figure 2. In carrying out my improvement I dispense with the major portion of these ferrules by providing 5 the improved ferrule above described. This ferrule is screwed in against the packing in the usual manner. Suitable sockets 19 are provided in the face of the flange 17 for engagement by a suitable tool in turning the 10 ferrule into position. These engaging sockets, however, may be provided in the periphery of the flange 17, as shown in Fig. 3, in which event a slightly different tool is used in applying the ferrule; and, if desired, 15 grooves or the like, 20, may be provided in the face of the flange 17 should it be desired to use still another form of tool in turning the ferrule into position. This latter modification is shown in Fig. 4. In packing the 20 tubes to which no ferrule is applied, the packing is positioned in the space surrounding the same and tamped or pressed firmly inwardly against the bottom shoulder 13, preferably packing or filling the entire space 25 from said shoulders out to or flush with the outer surface of the tube sheet. The packing is swedged or pressed laterally into the grooves provided by the screw threads 14, thus retaining the packing securely in position without the aid of individual ferrules 30 or other retaining means.

As shown in Fig. 1, there will be a number 35 of tube ends near the edges of the tube sheets which will not be covered by the flanges 17 of the ferrules 16. To these tube ends, however, may be applied the ordinary individual 40 ferrules, 21, such as have heretofore been employed in connection with all the tube ends of a condenser. The clearance shown between the shoulders of the flange 17 and the tube ends in Fig. 2 of the drawings is to 45 permit of longitudinal expansion and contraction of the tubes, as will be readily appreciated by those skilled in the art.

45 In Fig. 5 I have shown another modified form of ferrule in which the outer flange is a separate member. The body of the ferrule 22, is preferably the standard ferrule now in use but with the end screw 50 threaded and somewhat tapered. A screw-threaded ring 23, is provided which may be screwed over the tapering thread until it binds. This arrangement permits the use of 55 standard ferrules. The extension may be differently shaped and applied in other ways, for example it may be simply a ring 60 pressed over the end of the usual ferrule or positively locked thereto by means of a set screw or other suitable fastening means.

60 By the use of my improved ferrule a great economy is effected. In the case of condensers having several thousand tubes it is the practice in some cases to provide a packing 65 at each end of each tube and in other cases at one end only, the unpacked ends being ex-

panded to engage the tube sheet. In either case by the use of my improved ferrule nearly six-sevenths of the number of ferrules formerly required may be dispensed with.

Another advantage of my construction is that a freer flow of water through the tubes is possible since there are fewer projecting ferrule ends to interfere with the circulation.

It will be obvious to those skilled in the 75 art that the present invention is susceptible of change and modification, and accordingly it is not desired to limit or restrict the same except where limitations appear in the appended claims.

I claim:

1. The combination in a condenser having the usual tube sheet and tubes projecting therethrough, of a ferrule designed to engage the tube sheet around one of said tubes, 85 and provided with means overlying the end of the latter and the tube ends immediately surrounding the same.

2. The combination in a condenser having the usual tube sheet and tubes projecting 90 therethrough, of retaining means engageable with the tube sheet and overlying a plurality of the ends of said tubes to prevent outward displacement of the latter.

3. The combination in a condenser having 95 the usual tube sheet and tubes projecting therethrough, of a member engaging said tube sheet around one of said tubes and provided with means adapted to overlie the end of said tube and a plurality of other tube 100 ends for limiting outward movement of said tubes.

4. A condenser having a tube sheet with a large number of openings therethrough, tubes the ends of which are received within 105 said openings, the outer ends of said openings being screw-threaded, metallic packing pressed between said tube ends and said screw threads to engage the latter and resist movement as the tube expands and contracts, 110 and a plurality of ferrules screwed into certain of said openings, and each having a portion which restricts outward movement of the tube in the same opening and having an extension overlying the ends of all the adjacent tubes to restrict outward movement of 115 the latter, whereby a smaller number of ferrules is required than the number of tubes.

5. As a new article of manufacture a condenser ferrule having an inward projection to limit the movement of the tube which the ferrule surrounds and having a separate member secured thereto and providing an outward extension to limit the movement of 125 adjacent tubes.

In testimony whereof, I have subscribed my name.

FRANK E. PAYNE.
